UNITED STATES PATENT OFFICE.

CHARLES W. LANG, OF PHILADELPHIA, PENNSYLVANIA.

CARTRIDGE-FEED MECHANISM FOR BREECH-LOADING FIREARMS.

1,359,607.

Specification of Letters Patent. Patented Nov. 23, 1920.

Application filed January 16, 1917. Serial No. 142,740.

To all whom it may concern:

Be it known that I, CHARLES W. LANG, a citizen of the United States of America, residing at Philadelphia, in the State of Pennsylvania, have invented certain new and useful Improvements in Cartridge-Feed Mechanism for Breech-Loading Firearms, of which the following is a specification.

This invention has for its object to provide means that will operate automatically by the opening of the breech closure of a firearm to seize a cartridge presented to the receiver above the breech closure, press the cartridge downward into position in front of the breech block that will insure the introduction of the cartridge into the chamber of the gun as the breech block closes, and return to position for receiving a succeeding cartridge when the breech is closed.

In carrying out the invention, the opening of the receiver is tapered rearwardly, so that while its front portion is of transverse dimension sufficient to freely pass a cartridge to a position in line with the bore, its rearward portion forms a cradle that receives and supports the cartridge case in a downwardly and forwardly inclined position, with the lower edge of the butt end slightly intersecting the path of the breech bolt, and with the point of the cartridge directed well toward the chamber of the gun; and coacting with this cradle or support, is a gripping foot, which is opened up to receive the cartridge whenever the breech bolt is closed, but presses upon the cartridge and holds it to its position in the cradle whenever the breech bolt is open; the pressure face of the foot being parallel to the inclined axis of the cartridge, so that it firmly grips the cartridge in its position pointed toward the chamber of the gun. The presser foot is preferably pivoted and develops its gripping effect under the reaction of a spring, the breech bolt acting upon it as a cam to open it in opposition to its spring when the breech bolt closes, and receding from its control so as to leave it free to act under its spring whenever the breech bolt opens.

The invention will be fully understood upon reference to the accompanying drawing, in which—

Figure 1 is a vertical sectional view of the receiver of a breech loading firearm embodying the present invention; the section being

taken through the presser foot, and the parts being in the positions assumed when the breech bolt is open;

Fig. 2 is a view of a portion of the structure shown in Fig. 1, but with the parts in the positions assumed when the breech bolt is closed;

Fig. 3 is a vertical longitudinal section of parts shown in Fig. 1;

Fig. 4 is a top plan view of the receiver and a cartridge in the relation thereto shown in Figs. 1 and 3; and

Fig. 5 is a perspective view of a breech bolt.

1 represents the receiver, 2 the breech bolt, and 3 the feed throat of a breech-loading firearm. The throat 3 is provided with a rearwardly tapering portion 3^a, proportioned so that it admits nearly the major diameter of a cartridge case A, near the forward end of the latter, but admits only a minor diameter or chord of the case at its rear end, with the result that the cartridge lies in the tapered portion 3^a of the throat in a downwardly and forwardly inclined position, as shown more clearly in Fig. 3, whenever the breech bolt is drawn rearwardly from beneath the cartridge. In other words, the rear tapered portion 3^a of the receiver throat forms a cradle for the cartridge that presents its forward end safely toward the bore of the gun and dips its rear end slightly within the path of the breech bolt, so that when the breech bolt closes, the cartridge will be projected with certainty into the chamber of the gun.

In rapid fire guns where cartridges are fed in rapid succession to the position shown in Fig. 2 and must as rapidly assume the position shown in Fig. 3 each time the breech bolt opens, mal-functioning of the gun sometimes results from the rebounding or hanging of the cartridge, or the failure of its forward end to assume proper depression. To avoid this disadvantage, the present invention provides a presser foot 5 that is so controlled by the breech closure 2 as to assume the open or receptive position shown in Fig. 2, when the breech bolt is closed and the depressed or gripping position shown in Figs. 1 and 3, whenever the breech bolt is open. The presser face of the foot 5 is inclined parallel to the position assumed by the cartridge in its cradle 3^a, so that the cartridge is

forced to and retained in the position shown in Figs. 1 and 3, until it is moved forwardly by the closing breech bolt and delivered into the chamber of the gun. Pressure of the foot 5 is preferably developed by a spring 6 which is overcome by a cam face 7 on the breech bolt 2, acting upon the heel 8 of the presser foot, when the breech bolt closes, in order to open the presser foot, or which is left free to 10 depress the foot whenever the breech bolt is open. The cam face 7 preferably extends through a considerable proportion of the length of the breech bolt, so that movement of the presser foot is quite gradual, and work 15 to be performed in operating it is well distributed.

The invention is obviously of advantage however the cartridge be introduced into the gun, but is of greatest advantage when 20 cartridges are fed from a magazine in rapid succession, as suggested in Fig. 1, and when associated with a magazine, the presser foot may act to hold back a succeeding cartridge until the cartridge being introduced is well 25 out of the way, so that the succeeding cartridge will not be tilted or permitted to approach its position over the throat of the

receiver, with one end in advance of the other, to any objectionable degree.

I claim:—

1. In a breech loading fire arm, a breech closure, an inclined cartridge seat coating therewith, means for feeding a cartridge on to said seat, and a presser foot adapted to hold the cartridge against said seat until the 35 cartridge is well advanced into the chamber.

2. In a structure such as is set forth in claim 1, means tending to move the presser foot into active position, and counteracting means traveling with the breech closure and 40 permitting said presser foot to move into active position as the breech opens.

3. A structure such as is set forth in claim 2, in which the presser foot is pivoted at one side of the cartridge seat with movement 45 transverse to the cartridge feed.

4. A structure such as is set forth in claim 3, in which a heel on the presser foot coacts with a longitudinal cam face on the breech closure.

The foregoing specification signed at Newark, New Jersey, this 9th day of January, 1917.

CHAS. W. LANG.
